NEEDLE-VIBRATING MECHANISM FOR
SEWING MACHINES

George M. Eames, Bridgeport, Conn., assignor to
The Singer Manufacturing Company, Elizabeth, N. J., a corporation of New Jersey

Application December 22, 1933, Serial No. 703,538

8 Claims. (Cl. 112—158)

This invention relates to improvements in needle-vibrating mechanisms for zigzag stitch sewing machines and more particularly in the needle-vibrating mechanism disclosed in the U. S. patent of C. F. Gray, No. 1,020,089, Mar. 12, 1912.

The primary object of this invention is to provide a needle-vibrating mechanism of simple construction and quickly adjustable for effecting the production of either straightaway or zigzag stitch production of either straightaway or zigzag stitch seams. A further object of the invention is to provide a needle-vibrating mechanism which lends itself to convenient assemblage of the component parts thereof in a sewing machine.

With these and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front side elevation, partly in section, of a sewing machine containing the improved needle-vibrating mechanism. Fig. 2 is a rear side elevation of the machine. Fig. 3 is a section of the bracket-arm in substantially the vertical plane containing the transverse crank-shaft. Fig. 4 is a vertical section of the adjusting spindle, substantially on the line 4—4 of Fig. 3. Fig. 5 is another vertical section of the adjusting spindle, substantially on the line 5—5 of Fig. 3. Fig. 6 is a horizontal section of the crank-end of the adjusting spindle. Fig. 7 represents a perspective view of the crank-shaft bushing.

The present improvements have been embodied in a sewing machine constructed substantially in accordance with that forming the subject of my pending patent application Serial No. 691,938, filed Oct. 3, 1933.

Referring to the drawings, the sewing machine has a work-supporting bed-plate 1, from one end of which rises the hollow standard 2 of a bent bracket-arm 3, overhanging the bed-plate and terminating in a head 4 closed at its outer end by a detachable cover-plate 5.

Rotatably journaled in suitable bearings provided in said bracket-arm 3 is a horizontally disposed main or needle-reciprocating shaft 6 extending lengthwise of the bracket-arm and carrying at one end a driving pulley 7. At its oppo-

site end, the main shaft 6 carries a counterbalanced crank 8 provided with a crank-pin 9, connected by a jointed link 10 to a collar 11 secured upon a needle-bar 12, carrying at its lower end a needle 13.

The needle-bar 12 is journaled for endwise vertical reciprocation in suitable bearings provided in a vibratory gate 14, hung at its upper end upon a fulcrum-pin 15 for swinging movements of the gate 14 about a pivotal axis transverse to the axis of rotation of the main shaft 6.

Extending horizontally from the lower end of the vibratory gate 14, within a suitable guideway slot in the lower portion of the bracket-arm head 4, is an arm 16 of which the free end at the outside of said head carries a pivot-block 17. Embracing the pivot-block 17 is the forked lower end of a rock-arm 18 depending from the front end of a short rock-shaft 19 disposed horizontally transverse to the main shaft 6 and suitably journaled at the under side of the bracket-arm head. Extending upwardly from the rock-shaft 19, at the rearward side of the head 4, is a rock-arm 20 of which the free end is connected by a pivot-screw 21 to one end of a pitman 22 disposed horizontally and externally at the rearward side of the bracket-arm 3.

At its opposite end, the pitman 22 is apertured to receive a crank-pin 23 formed by a shouldered boss at the rearward side of an adjustable crank-member 24, the apertured end of the pitman being held upon the crank-pin 23 by a screw 25. The crank-member 24 is adjustably carried by a flange 26 upon the rearward end of a tubular crank-shaft 27 extending horizontally transverse to and disposed below the main shaft 6, said crank-member being secured upon the rearward face of the flange 26 by a pivot-screw 28 at one side of the axis of the crank-shaft 27 and by a guide-screw 29 at the opposite side of said crank-shaft axis. The guide-screw 29 passes through an arcuate slot 30, provided in the crank-member and having the pivot-screw 28 as its center of curvature.

The flange 26 of the crank-shaft 27 and the crank-member 24 carried thereby are housed in a recess 31 formed by a depressed portion of the rearward wall of the bracket-arm 3, the pitman 22 extending through a slot 32 in the side wall of said recess. A cover-plate 33 for the recess is secured by a screw 34 upon the bracket-arm to provide for conveniently swinging the cover-plate upwardly into a recess-exposing position illustrated by dot-dash lines in Fig. 2. The inner wall 35 of the recess 31 is provided with a

bearing aperture 35 for the rearward end of the crank-shaft 27, the forward end of said shaft being disposed in a bushing 36 rotatably journaled in a bearing aperture 37 in the front wall of the bracket-arm 3. At its forward end the bushing 36 has a flange 38 into which are threaded set-screws 39 for securing the bushing to the crank-shaft 27, said flange 38 having a segmental recess 38' in its front face providing opposed stop-shoulders 40, 41. Secured upon the crank-shaft 27, within the bracket-arm 3, is a spiral gear 42 engaged by a spiral driving gear 43 carried by the main shaft 6, said gears being constructed so that the crank-shaft 27 is rotated at one half the speed of rotation of the main shaft 6.

Journaled for turning movement in the crank-shaft 27 is a crank-member adjusting spindle 44, having at its rearward end an eccentric-head 45 fitted within a yoke-shaped recess 46 provided in the inner face of the crank-member 24. For conveniently turning the adjusting spindle 44 manually, a manipulating member 47 is secured by a set-screw 48 upon the projecting front end of said spindle. Carried by the manipulating head 47 is a stop-pin 49 which extends between and contacts with the stop-shoulders 40, 41 of the crank-shaft bushing 36, to limit angular adjustment of the spindle 44. A friction-washer 50 is interposed between the spindle-head 47 and the front end of the crank-shaft 27, said friction washer acting to maintain the adjusted position of the spindle, i. e., acting to induce rotation of the spindle with the crank-shaft during the operation of the machine.

In its preferred embodiment, the arrangement is such that the crank-pin 23 is in axial alignment with the crank-shaft 27 at one of the limits of angular movement of the adjusting spindle 44, determined by engagement of the stop-pin 49 with one of the stop-shoulders 40, 41. It will, of course, be understood that in this position of the crank-pin 23, the pitman 22 remains stationary during the operation of the machine, whereby the needle-bar 12 is reciprocated in a fixed path. By now partly rotating the adjusting spindle 44 manually, for instance until the stop-pin 49 engages the other of the stop-shoulders 40, 41, the turning of the eccentric-head 45 swings the crank-member 24 about the pivot-screw 28, thereby shifting the crank-pin 23 off center with respect to the axis of the crank-shaft 27. When the machine is now operated, the pitman 22 is reciprocated to impart vibratory movements to the gate 14, whereby the needle is successively reciprocated in spaced paths.

Any suitable loop-taking means may be employed as complementary to the needle in the formation of stitches, while work-advancing means and an opposed presser-device may or may not be embodied in the machine, dependent upon the character of the work.

Having thus set forth the nature of the invention, what I claim herein is:

1. In a sewing machine, a laterally vibratory frame, a needle-bar journaled in said frame for endwise reciprocation, a rotary crank-shaft, means for rotating said shaft; a crank-member adjustably carried by said crank-shaft; a pitman connected to said crank-member and to said vibratory frame, an eccentric disposed in operative engagement with said crank-member to effect adjustment thereof, and manually operable means for turning said eccentric relatively to said crank-member.

2. In a sewing-machine, a laterally vibratory

frame, a needle-bar journaled in said frame for endwise reciprocation, a rotary crank-shaft, means for rotating said shaft, a recessed crank-member adjustably carried by said crank-shaft, a pitman connected to said crank-member and to said vibratory frame, a crank-member adjusting eccentric disposed in the recess of said crank-member, means for inducing rotation of said eccentric with said crank-shaft during the operation of the machine, and manually operable means for turning said eccentric relatively to said crank-shaft to thereby effect adjustment of said crank-member.

3. A sewing machine having a bracket-arm, a vibratory needle-bar frame mounted in said bracket-arm, a rotary actuating shaft journaled in said bracket-arm, a tubular crank-shaft rotatably journaled in said bracket-arm and geared to be driven by said actuating shaft, a crank-member adjustably carried by said crank-shaft, a pitman connected to said crank-member and to said vibratory frame, an adjusting spindle extending lengthwise of and journaled in said tubular crank-shaft, and an eccentric carried by said adjusting spindle in operative engagement with the crank-member to effect adjustment of said member.

4. A sewing machine having a bracket-arm, a vibratory needle-bar frame mounted in said bracket-arm, a rotary actuating shaft journaled in said bracket-arm, a tubular crank-shaft rotatably journaled in said bracket-arm extending transversely of and geared to be driven by said actuating shaft, a crank-pin carrying member pivotally mounted upon said crank-shaft for adjustment of the crank-pin into and out of alignment with the axis of rotation of the crank-shaft, a pitman embracing said crank-pin and operatively connected to vibrate said frame, an adjusting spindle extending lengthwise of and journaled in said tubular crank-shaft, and an eccentric carried by said adjusting spindle in operative engagement with the crank-pin carrying member to effect adjustment of said member.

5. A sewing machine having a bracket-arm, a vibratory needle-bar frame mounted in said bracket-arm, a rotary actuating shaft journaled in said bracket-arm, a tubular crank-shaft rotatably journaled in said bracket-arm extending transversely of and geared to be driven by said actuating shaft, a crank-member adjustably carried by said crank-shaft, a pitman actuated by said crank-member and operatively connected to vibrate said frame, an adjusting spindle extending lengthwise of and journaled in said tubular crank-shaft, an eccentric carried by said adjusting spindle in operative engagement with said crank-member to effect adjustment thereof, and means for inducing unison rotation of said crank-shaft and adjusting spindle during the operation of the machine.

6. A sewing machine having a bracket-arm, a vibratory needle-bar frame mounted in said bracket-arm, a rotary actuating shaft journaled in said bracket-arm, a tubular crank-shaft rotatably journaled in said bracket-arm extending transversely of and geared to be driven by said actuating shaft, a yoked crank-member adjustably carried by said crank-shaft at one end thereof, a pitman actuated by said crank-member and operatively connected to vibrate said frame, an adjusting spindle extending lengthwise of and journaled in said tubular crank-shaft, a crank-member adjusting eccentric carried by said adjusting spindle and embraced by the yoke of said crank-member, and opposed stops limiting turn-

ing movements of said adjusting spindle relatively to said crank-shaft.

7. A sewing machine having a bracket-arm, a vibratory needle-bar frame mounted in said bracket-arm, a rotary actuating shaft journaled in said bracket-arm, a tubular crank-shaft rotatably journaled in said bracket-arm extending transversely of and geared to be driven by said actuating shaft, a yoked crank-pin carrying member pivotally mounted upon one end of said crank-shaft for adjustment of the crank-pin into and out of alignment with the axis of rotation of the crank-shaft, a pitman embracing said crank-pin and operatively connected to vibrate said frame, an adjusting spindle extending lengthwise of and journaled in said tubular crank-shaft, an eccentric carried by said adjusting spindle and embraced by the yoke of the crank-pin carrying member, a bushing carried by said crank-shaft and having opposed stop-shoulders, and a stop-pin carried by said adjusting spindle between said stop-shoulders.

8. A sewing machine having a bracket-arm, a laterally vibratory frame mounted in said bracket-arm, a needle-bar journaled in said frame for endwise reciprocation, a rotary actuating shaft extending lengthwise of and journaled in said bracket-arm, connections with said actuating shaft for reciprocating said needle-bar, a crank-shaft rotatably journaled in said bracket-arm extending transversely of and geared to be driven by said actuating shaft, a crank-pin carrying member adjustably mounted upon said crank-shaft at the rearward side of said bracket-arm, an eccentric disposed in engagement with the crank-pin carrying member to effect adjustment of said member, an eccentric-carrying spindle, a manipulating member carried by said spindle at the front side of said bracket-arm for turning said spindle relatively to said crank-shaft, and friction means for inducing rotation of said spindle with said crank-shaft during the operation of the machine. 5 10 15 20
